THOMAS E. FOGALSANG AND BERTHA McCUTCHEON, OF SAN FRANCISCO, CALIFORNIA,
ASSIGNORS TO JOSEPH A. MOROSS, OF SAN FRANCISCO, CALIFORNIA.

HOT-WATER-BAG HEATER.

1,002,253.

Specification of Letters Patent.

Patented Sept. 5, 1911.

Application filed October 12, 1910. Serial No. 586,736.

To all whom it may concern:

Be it known that we, THOMAS E. FOGALSANG and BERTHA McCUTCHEON, both citizens of the United States, residing in the 5 city and county of San Francisco and State of California, have invented new and useful Improvements in Hot-Water-Bag Heaters, of which the following is a specification.

Our invention relates to hot water bags 10 and pertains especially to a hot water bag to be heated by electricity.

The object of the invention is to provide a simple, practical electrically heated hot water bag in which a naked electrode can 15 be used; the electrode carried by the stopper which can be screwed into the hot water bag like any ordinary stopper, or otherwise suitably attached, and providing novel means for ready connection and disconnection with the terminals of the wires carrying 20 the current.

A further and particular object is to do away with the changing of the water when it gets cold by so proportioning the heating 25 unit or element that it will keep the water at the desired temperature as long as the current is applied.

The invention consists of the parts and construction and combination of parts as 30 hereinafter more fully described and claimed having reference to the accompanying drawings, in which—

Figure 1 is a plan view in partial section of the bag and stopper, showing the 35 application of the invention. Fig. 2 is a section on X—X, Fig. 1. Fig. 3 illustrates a modification of the invention on a reduced scale.

A, represents a hot water bag of any 40 suitable description.

2 is a stopper of hard rubber or other suitable dielectric material, screwed, or otherwise appropriately secured in the mouth of the bottle to form a closure therefor, and at 45 the same time to form a support for the heating element. As shown in Fig. 1, this heating element consists of two non-corrosive high resistance electrodes 3, which are suitably fastened to two wires 4, embedded 50 in and extending through the stopper 2. The wires 4 where they extend through the stopper have a snug fit therewith so as to prevent leakage, and if desired a rubber or an equivalent gasket 5 may be interposed

between the stopper 2 and its seat 6. The 55 wires 4 project above the top of the stopper and form male members which are adapted to telescope with the female or sleeve conducting-couplers 7, which are carried by and in electrical union with the terminals 60 of the cords 8. These metallic sleeves 7 fit in a bushing 9 of suitable insulating material, such as hard rubber, fiber or porcelain. The lower ends of the electrodes which project within the bag A are suitably spaced and insulated from one another by a bulb or spacing member 10, of hard rubber or the like. In Fig. 3, we have shown the electrical heating unit as wound around an insulating post 10'. 70

In practice, a suitable quantity of water is placed in the bag and the stopper 2 screwed in, in the usual fashion, allowing the electrode or electrodes to be immersed in the water within the bag. In order to 75 keep the electrode out of contact with the sides of the bag, as the heat of the electrode might under some circumstances, injure the rubber, the insulation 10 or 10^a may be of sufficient diameter or size to support the 80 inner end of the electrodes away from the sides of the bag.

To heat the water it is only necessary to connect the projecting ends of the wires 4 with a suitable source of electric current 85 through the medium of a coupler 9 and electrical connection 7—8. As soon as the water is heated to a sufficient temperature the electrical connection can be easily broken by removing the coupler 9. If the water has cooled off in the bag it is quickly reheated by reestablishing the electric circuit, without having to change the water or even disturb the patient.

Having thus described our invention, 95 what we claim and desire to secure by Letters Patent is—

1. The combination of a hot water bag and a stopper therefor, said stopper of insulating material and carrying an exposed 100 electrode, said electrode adapted to project within the bag and to be removable therefrom with the stopper, and having means on the outside of the stopper for connection with an electrical circuit, said means comprising a conducting sleeve telescoping with an extending portion of the electrode, and a bushing of insulating material receiving

and inclosing the sleeve and pierced to admit a conducting wire to the electrode.

2. The combination of a collapsible hot water bag, a stopper therefor of dielectric material in which are embedded a pair of conducting wires, electrodes connected with the said wires and projecting within the bag but removable therefrom with the stopper, and an enlargement fixed by the electrode within the bag and carried by the electrodes and co-operating with the stopper

to hold the electrodes out of contact with the bag.

In testimony whereof we have hereunto set our hands in the presence of two subscribing witnesses.

THOS. E. FOGALSANG.
BERTHA McCUTCHEON.
